WRAPPING AND BANDING MACHINE

Francis X. Malocsay, Upper Saddle River, N. J.,
assignor to International Banding Machine
Company, a corporation of New York

Application March 12, 1934, Serial No. 715,124

6 Claims. (Cl. 93—2)

This invention relates to the art of banding and wrapping cigars, and more particularly to the wrapping of transparent wrappers and bands around cigars.

5 It is among the general objects of the present invention to provide an improved wrapping and banding mechanism, which will be entirely automatic in its operation.

In some of my prior applications for example, 10 in the wrapping and banding machine described in Serial No. 653,609, filed January 26, 1933, I have shown similar mechanisms for accomplishing similar objects, i. e. mechanisms, adapted to fold and secure a wrapper and a band simultaneously around a cigar, and many of the mechanisms and appurtenances to be mentioned and described are alike in both machines. There is, however, this difference in the methods of 15 wrapping and banding a cigar:—According to the prior inventive concept the cigar was wrapped directly into the wrapper and the cigar band was applied over it, encircling the wrapper; according to the present concept the cigar band is secured directly to the cigar and the wrapper 20 covers the band, so that the latter may be seen and read through the transparent wrapper. This difference in objected aim and results obtained calls for modifications of the folding and wrapping means and the improvements proposed and 25 described hereinafter are directly concerned with effecting these deviating results in the most efficient, simplest and most economical manner. Some of these modifications which are not directly concerned with the wrapping and banding 30 operations themselves, but with the feeding of the wrapper and band material to a common wrapping and banding position, are shown in my copending application, filed February 27, 1934, Serial No. 713,116, but the improvements described hereinafter are confined to the wrapping 35 and banding operations and mechanisms themselves.

The machines themselves, both in the last mentioned as well as in the present application, 40 follow the same principles in the general arrangement, to wit: The wrapper feed rollers are located at the rear of the machine, while the band magazine and band feeding device is positioned on the opposite or front side of the machine, separated from each other by the rectilinear cigar feeding and delivery path toward which both devices feed a wrapper and a band respectively, in such a way that the band is put underneath the wrapper by means of a reciprocating gripper; thus both the band and the

wrapper are deposited at the banding and wrapping position which consequently is located at the crossing point of the band and wrapper conveyor path; i. e. above the aforesaid reciprocating gripper and that of the cigar feed and delivery path. The wrapping device itself is positioned above this crossing point. When the band with the superimposed wrapper has arrived at this point, a cigar is pushed from underneath into said combined wrapper and band by 10 a reciprocating vertical plunger and carried upwardly a little way into the banding and wrapping position properly, which then remains stationary during the rest of the wrapping, banding and end-sealing operations, and when these are 15 finished, it can be foreseen that the result will be a cigar wrapped into a transparent wrapper with the band being visible through the latter.

Considered more in detail it is among the objects of the present invention to provide a wrap- 20 per-and-band-applying device which will apply a wrapper over a band and both in unison over a cigar in a wrapping and banding position.

Another object of the invention is to provide means whereby cigars are fed separately and in 25 spaced relationship into this position.

Another object of the invention is to provide a wrapper and band applying device which will fold a band and a superimposed wrapper over three sides of a cigar from above while carrying 30 the cigar together with the wrappings into a wrapping and banding position.

A further object of the invention is to provide a mechanism which will complete the banding and wrapping operations from this point on 35 without moving said cigar.

Another object of the invention is to provide means whereby the cigar, before it is pushed into its band and wrapper, is exactly adjusted in an axial or longitudinal direction so that the over-reaching ends of the wrapper will be of equal 40 and suitable lengths.

Another similar object of the invention is to provide novel centering means whereby the cigar, before it is pushed into its band and wrapper, 45 is exactly adjusted in a direction normal to its own axis, so that it will meet the band and wrapper in the proper place.

A further object of the invention is to provide wrapping means adapted to fold band ends and 50 wrapper ends around the fourth or underside of the cigar simultaneously.

A further object of the invention is to provide means whereby, before the wrapper ends are folded into place, the ungummed end of 55

the band is "tucked" inwardly against the body of the cigar.

Another object of the invention, corollary to the last named, is to provide means whereby, before the final folding of the wrapper ends, the gummed and moistened end of the band is pressed against the above mentioned end, so that the band is positively sealed before the wrapper is closed over it.

10 Another object is to provide novel and adjustable actuating means for both "band folding and tucking" devices.

Other more specific objects and advantages of the device will appear as the nature of the improvements are better understood, the invention consisting substantially in the novel arrangement, and correlation of instrumentalities herein fully described and illustrated in the accompanying drawings wherein similar reference 15 characters are used to describe corresponding parts throughout the several views and then finally pointed out and specifically defined and indicated in the appended claims.

The disclosure made the basis of exemplifying the present inventive concept suggests a practical embodiment thereof, but the invention is not to be restricted to the exact details of this disclosure, and the latter therefore is to be understood from an illustrative rather than a restrictive standpoint. It will be also understood that the various features of the present invention disclosed may be separately applicable despite their cooperation herein shown.

This invention may be more fully understood 35 from the following description in connection with the accompanying drawings, in which—

Fig. 1 is a top plan view of a complete banding and wrapping arrangement, showing the cigar feeding and discharge table, the wrapper feed mechanism (with the wrapper roll omitted) on the right-hand or rear side of the table and the band feed mechanism on the left-hand or front side of the table. In the center is shown a spread-out wrapper with a band underneath, which has just been fed over a cigar, coming from the cigar feeding rack, shown in the upper part of the top plan view. Cigar and band are indicated in dotted lines.

The folding and wrapping mechanism itself, which is supposed to be located just above said wrapper, is not shown in this view.

Fig. 2 is a front elevation (sectional in parts) of this folding and wrapping mechanism, viewed from across the table, with the band and wrapper feed devices omitted, and showing the vertical plunger in the act of elevating a cigar, carrying the band and wrapper on its top into the wrapping position.

Fig. 3 is a cross-sectional elevation, taken along the line 3—3 of Fig. 2, also depicting the cigar feeding mechanism and the devices for actuating the cigar holding and wrapping and banding means themselves.

Fig. 4 is a view partly sectional similar to Fig. 2, but taken just behind the operating parts shown in full in the upper half of Fig. 2, at the same time showing the plunger having elevated the cigar fully into its stationary wrapping position.

Fig. 5 is a fractional view of the last illustration, showing the mechanism of the tucking finger which presses the gummed end of the band against the cigar.

Fig. 6 is a detail side view, partly in section, 75 which shows the wrapping jaws and the fold-

ing finger which pushes the ungummed end of the band into closing position.

Fig. 7 is a fractional plan view of the band folding plates with the wrapping jaws shown in cross-section, the view being taken along the line 7—7 of Fig. 4.

Figs. 8 to 11 are similar views, more or less shown diagrammatically, and illustrating consecutive steps of the banding and wrapping operations.

Similar characters denote similar parts throughout the different views.

Referring more in detail to the figures listed, we see in Figs. 1 and 2, the cigars C, supported on the plate F advanced in spaced formation to 15 a position beneath the wrapping mechanism D and beneath the wrapper W together with the band B, just over the plunger 3 when the latter is in its lowest position.

The cigars are originally fed automatically 20 from a hopper, not shown in the drawings, but located at the upper end of the table I (above what is shown in the drawing of Fig. 1). The type of this mechanism is fully described and illustrated in my former Patent No. 1,653,641, filed December 27, 1927, as also in the copending applications, Serial No. 492,437 (Cigar banding machine) filed October 31, 1930, or in Serial No. 519,347 (Cigar handling machines), filed March 2, 1931. 30

The cigars are first advanced in close formation by advancing bars to a separator (not shown) from which point they are advanced in spaced formation by the feed racks 2—2, as shown. The spaced cigars are prevented from 35 rolling or being disturbed, while not supported by the reciprocating and temporarily lowered feed racks, by a feeler arm (not especially shown) which keeps them under tension during these intervals.

The actuating mechanism of the feed racks 2—2 is best shown in Fig. 3. The racks are mounted on a reciprocating frame 4, slidably supported on the plate 5, secured to a vertically reciprocating stem 6, guided in the bearing 7, 45 forming a part of table frame I. Stem 6 is slotted and carries a roller 8 within its slot which is engaged by the finger 9 through an aligned and corresponding slot 7a in the bearing 7. The finger 9 is adjustably fastened to the cam lever 10, 50 the latter being loosely mounted on shaft 11 and lifted periodically by another cam (not shown) against the tension of spring 12, while at the same time the slideable frame 4, which properly carries the feed racks, reciprocates the same in 55 a horizontal direction toward and away from the wrapping mechanism by means of a connecting rod and eccentric (not shown in the present application).

In Fig. 3 the feed racks are shown in their low- 60 ered position, having released their sideward pressure against the cigars by dropping downwardly and moving in an arc toward the left end of the machine underneath the following cigar and rising again so that their upwardly extending ears 13 register again with the spaces between the cigars. When now they move again to the right, they will advance the spaced cigar another step, placing again the leading cigar in line with the wrapping mechanism D and over 70 the elevating plunger 3 (see Figs. 2 and 8), the reciprocating and plunging motions being so regulated and activated that they are in perfect synchronization with the time it takes to band and wrap one cigar after the other. 75

While the cigars thus are advanced step by step from the hopper toward the wrapping mechanism, the heads of the cigars which, looking at the top plan view in Fig. 1, are to the right, follow a rail 14 which runs parallel with the feed racks 2-2 to the point where the cigars commence to be spaced. From this point the rail is adjusted to form a slight angle (about $\frac{1}{16}$ " per foot) with the racks, terminating at the wrapping mechanism D where it is nearest to the feed rack. As the cigars are advanced they are gradually shifted endwise to the left so that when they arrive above the elevating plunger 3 they are in proper relation to the band and wrapping mechanism D, eliminating thereby the necessity of providing a movable finger, moving each cigar endwise to a fixed gauge, which might damage the delicate end (on the left side) by any pressure applied thereto.

With the cigar properly gauged into the right position above the elevating plunger (see Fig. 8) the latter lifts the cigar to a location between the universal centering jaws 15, 16, which are then in their open position. Then the jaw 15, moving to the right, and the jaw 16, moving to the left, will hold the cigar in a light yielding grip, centering it regardless of its width, with the band and wrapper having arrived above it, where they have been fed into this position by the wrapper feed and band feed mechanism, mentioned before and described in the copending application, Ser. No. 713,116.

Universal centering jaws

In former applications, i. e. Ser. No. 653,609, centering jaws were shown which substantially perform the same function. The arrangement to be disclosed hereinafter is, however, different, more simplified and effective. Jaw 16 is substantially the same as in former devices, except that it has openings 16a through which the feed racks 2-2 can pass, while the jaw 15 is entirely suspended above the path of the cigar feed, so as to offer no obstruction in the path of the cigars, especially when exceptionally long cigars are to be wrapped, and also to facilitate the placing of the band over the cigar in any desired position in relation to the length of the latter. (See Fig. 8.) Jaw 16 is essentially a vertical one-armed lever, pivoted with its lower end on frame 1 (not shown) and a short distance from the upper end a horizontal connecting rod 18 is linked to the stud 17, provided on the jaw lever 16, while the other end of the rod is linked at 19 to the upwardly extending end of bell crank 20, fixedly secured on rocking shaft 21. The suspended jaw 15 is essentially a horizontal swing, suspended at two points 26 and 23 with one end formed as a T-shaped jaw and projecting beyond the suspension point 23. At the latter point member 15 is hung from link 22, pivotally suspended from a stud 24, secured in the main bracket 25, while the rear end is hung at point 26 from the downwardly extending arm 27 of the big bellcrank 28 which is pivotally suspended from another stud 29, secured in main bracket 25. The formerly mentioned bell brank 20 to which jaw 16 was linked, and the bell crank 28 to which jaw 15 is linked are coupled together by the vertical connecting rod 31, linked at its lower end to the free end of the bell crank 20 by means of the stud 32 and at the top end to the free end of the bell crank 28 by means of the stud 30. It should be apparent then, that if the rocking shaft 21 is turned in a counterclockwise sense (which move-

ment is effected by the tension of a spring, not shown) jaw lever 16 which can swing about its lower pivotal point, is drawn to the left, while jaw 15, forming the end of the doubly suspended swing is pushed to the right, thus clamping the elevated cigar between them. This arrangement assures a perfect centering of the cigar relative to the band, regardless of any variation in width or thickness of the cigars to be banded and wrapped. If, however, the shaft 21 is rocked in a clockwise sense (which movement is brought about by a cam device (not shown)) then jaw 15 is pulled to the left, and jaw 16 is pushed to the right, away from the cigar which is thus released and can thence be elevated by the plunger 3 and pushed into the band and superimposed wrapper in properly adjusted relationship.

While, however, the cigar is still held between the jaws 15 and 16 in the position shown in Fig. 3, the band and wrapper is supported loosely above the cigar, the ungummed end of the band resting on the reciprocating gripper 153 (which is shown in detail and described in the copending application, mentioned before) while the free gummed end rests on the upper edge of the T-shaped jaw 15. The top view of band and wrapper, showing its relative position to the cigar is shown in Fig. 1. While in this position, just before the jaws open again, the upper vertically moving plunger 35 reaches its lowermost position, resting on the wrapper, band and cigar under the tension of springs 35'-35' (Figs. 2 and 3) whereas as the wrapping jaws 36 and 37 are still in their opening position. The lateral edges of the wrapper are meanwhile supported on the blades 33 and 34 (Fig. 3).

The plunger 3 moves now further upwards, carrying the cigar, band, wrapper and upper plunger 35 with it, while the lower jaws 15 and 16 open up, as Fig. 9 indicates. As in further progress the cigar with band and wrapper enters between the wrapping jaws 36 and 37, the protruding lateral edges of the wrapper, as well as the ends of the band, are bent downward and then the jaws move inwardly toward the cigar, folding wrapper and band smoothly against the sides of the cigar until the cigar with band and wrapper, together with the upper plunger 35 reaches its extreme ultimate upper position where it is to remain stationary for the rest of the operations. Fig. 10 shows this, except that this view in its lower part anticipates a further progress, inasmuch as so far the elevating plunger 3 has not released its support of the cigar yet while the tucking finger 42 is still in its lower and non-contacting position. When the elevating plunger reaches its uppermost position, the left hand folding plate 38 moves a little to the right, just enough to bear underneath the wrapping jaw 36, as Fig. 10 indicates. Therewith the end of the brake member 39 (shown more plainly in its relative position and inter-connection on Figs. 3 and 4), which moves simultaneously with member 38, begins to exert a pressure against the inner surface of the upper vertical plunger slide 40 (Figs. 4 and 10) to prevent the same from moving downward under the tension of springs 35' when the supporting plunger 3 is lowered. As the jaws 36 and 37 are tightly gripping the half-wrapped cigar with the ends of the wrapper and band loosely hanging downward, it is clear that when the elevating plunger is now lowered, the cigar will remain suspended with its under side free to be operated upon. The folding plate 38, 75

as explained before, abides for a moment underneath jaw 36, but the hook-shaped member 41 whose mechanism will be explained in detail later, moves now inwardly, pressing against the downwardly hanging edge of the wrapper and causing thereby also the band end to assume a position inclined toward the underside of the cigar (shown in dotted lines in Fig. 10). Simultaneously with the lowering of the plunger 3, the tucker 42, which is situated in one of the free gaps of the three-formed plunger 3 (see Fig. 5) moves upward, pressing against the ungummed and uplifted end of the band, as shown in full lines (Figs. 10 and 5). The left hand folding plate 38 moves then further to the right, folding the gummed (and moistened) end of the band, together with the wrapper edge against the underside of the cigar, the tucker 42 slipping out of the way, as it is withdrawn from its contacting position by the continued downward motion of the plunger 3. At the same time the hook-shaped member 41 is moved back to its normal position by its bellcrank 43, as explained later (see Fig. 6). As the folding plate 38 reaches its extreme right-hand position, the right-hand folding plate 49 moves to the left to fold the remaining downward hanging edge of the wrapper, and as it continues to move to the left, now in union with the receding wrapping plate 38, the beveled edges of the two plates close up (being beveled in opposite directions) while the edge of the wrapper slips out upwardly from between them. Then both plates 38 and 49, moving to the left, to the position shown in Fig. 11, complete the closing of the band and wrapper sides.

End-creasing and delivering device

When the wrapping jaws 36—37 close upon the folded wrapper sides, the lugs 45 provided at both ends of the jaw plates (see Figs. 7, 8 and 9) 40 tuck in the overhanging wrapper ends so that they are creased approximately in the form of an X. In unison with the folding plate 49 travel three other members, i. e., the horizontally suspended bar 44 (see Figs. 3, 9, 10 and 11) and the creasing jaws 46 and 47. The bar 44 is bent in such a way that when folding plate 49 reaches the position shown in Fig. 11, the bar comes to rest on the upper face of cigar C which it slightly 50 contacts. Jaw 47 passes beneath the projecting ends of the wrapper while jaw 46 passes above them. When folding plate 49 reaches its extreme left position, jaw 47 moves up while jaw 46 descends. When at this moment the wrapping jaws 55 36 and 37 open up, removing thereby the lugs 45, the upper creasing jaws 46, moving down shear-like over the lower creasing jaw 47, makes a perfect bellowfold of the collapsed overhanging ends. As Fig. 7 indicates, the creasing jaws are so located that they operate within a gap in the wrapping jaws 36, 37. The creasing jaws are actuated to perform the described motions by cam and lever devices, but as these end-creasing elements do not form a claimed part of this invention and 60 said devices are more fully described in the mentioned applications, they are omitted in the drawings.

When the jaws 36, 37 open up at the end of the bellow-folding operation, the cigar is still held 70 securely in place by folding plate 49 and the bar 44, resting on top of it. The jaw 37, carrying member 41 with it, is lifted up by lever 43 (see Fig. 6) while the upper plunger 35 is raised by lever 48 (Fig. 3); then the cigar is carried out of 75 the wrapping mechanism D by the wrapping plate

49 and the bar 44 moving to the right. From this point the wrapped and banded cigar is carried still further to the heat-sealing means by mechanism not shown or claimed herein.

Summing up, while the wrapping jaws 36, 37, 5 the upper plunger 35, the left and right folding plates 38 and 49, the lower plunger 3 and the creasing jaws 46, 47 are substantially alike the corresponding parts, shown and described in prior applications, the tucking element 42 and the folding finger 41, for placing the band directly on the cigar, inside the wrapper, the suspended centering jaw 15 and the cigar feeding and gauging mechanism are claimed as novel improvements.

Band-folding member 41

The function of this member 41 is to direct the ungummed end of the band into the path of the tucker 42. It is substantially shaped like a hook, with a forked prong at the end and pivotally fastened on a stud 50, the latter being a fixed or integral part of the movable jaw 37. A cushion spring 51, seated in a little socket in the jaw plate tends to keep member 41 in its normal position, in which its end prong does not protrude into the space between the wrapping jaws 36—37. Any outward swing of the member 41 in the opposite direction is limited by the stop 52, a little bracket secured by the screws 53—53 to the jaw plate (see Figs. 2 and 6). Looking 30 at Fig. 6, one sees that the jaw 37 is hung from the shaft 64. The latter, as Fig. 2 indicates, is journalled in the U-shaped and curved frame 63 which itself with its free ends is rotatably linked to two members 90, fixedly seated on shaft 91. The lower part of the jaw is also freely hung at 73 in a similar way, and if there were so far nothing else to support the jaw casting, it is apparent that normally it would tend to drop downward. This drop however is limited by the 40 fixed stop 66, forming an integral part of the frame, on which the upper plunger 35 slides. The jaw carries a roller 65 (see Figs. 2 and 3) with which it comes to a rest on the stop 66, and when it is drawn inwardly by the counter-clockwise 45 rocking of shaft 89 and the jaw controlling links 88, the roller glides along the surface of the stop 66. Any lifting of the jaw however has to be effected by the bell crank 43 in a manner presently described. This bell crank, carried on 50 a stud 56, which is secured in the main bracket 25, is connected by stud 57 and the connecting rod 58 to a cam lever, actuated by a cam on the main cam shaft (shown in prior applications). Rigidly secured to the free end of the bell crank 55 43 by the stud 59 is the upright member 60 which with a forked top end 61 is adapted to embrace the stud 62, the latter forming a rigid portion of the frame 63 from which the wrapping jaw 37 is hung. When therefore the bell 60 crank is swung in a counter-clockwise sense, the forked member 60 will engage the stud 62, lifting up the frame 63 and thereby the whole jaw 37 together with the band-folding member 41.

An angular bracket 54, carrying a leaf spring 65 55 which acts as a cushion, is fixedly attached to the member 41. Another bracket 67 which has a downwardly curved nose 69, adapted to contact the leaf spring, is attached by screws 68 to the forked member 60. If now the jaw has 70 dropped as far as it can, arrested by the stop 66, the bell crank 43 (which has permitted this downward motion by its own clockwise movement and the lowering of forked member 60) continues its clockwise movement still a little 75

further, thereby pressing with the nose 69 upon the spring 55 and swinging the member 41 inwardly against the tension of spring 51. This sets the folding prongs at the end of the member 5 in action, thereby pushing the ungummed band end into the path of the tucker member 42.

Operation of tucking finger 42

The arrangement of the tucker finger, mentioned in connection with Figs. 8, 9 and 10, is best understood from Figs. 2, 4 and 5.

On the vertically moving frame 70, slidably mounted on bar 71 and guide 72, is secured by bolts 92-92 the cigar-elevating three-forked plunger 3. Bolted thereto is a bracket or bar 93, carrying a stud 74 on which is pivotally mounted the bell crank 75, having a stud 76 at one end, which by a link 77 is connected to stud 78 of the vertically slidable tucker member 42, 20 said member being provided with slots 79-79, engaging the guide pins 80-89 on plunger 3, over which it can reciprocatingly slide up or down, being normally kept in a lowered position by its own weight. The outwardly protruding arm of the bell crank carries a spring 84 whose lower end is attached to the free end of the spring-tensioned control arm 81, pivoted on stud 82, secured in bracket 83, which latter forms a fixed part of guide member 72. Both the bell 30 crank and the control arm 81 are provided each with a lateral lug 86 and 94 respectively, adapted to serve as abutments for controlling stops, presently to be described.

When the plunger 3 is in its lowest position, 35 the cigar-supporting surface is slightly lower than the cigar-feeding level, so that the feeding racks 2-2 can easily shift the cigar, to be wrapped and banded, onto the top of the plunger. At this moment the controlling arm 81 and the 40 protruding arm of the bell crank 75 will be about in the positions indicated by dotted lines in Fig. 2. Thereupon the plunger moves upwardly into the cigar-centering position, shown in Fig. 2, and the arm 81 and bell crank 75 assume the position 45 shown in full lines. At this moment, about, the lug 94 comes into contact with the adjustable abutting screw stop 85. Further upward movement of the plunger 3 will first stretch the spring 84, as the upward swing of the control arm 81 has come to a stop, thereupon the spring begins 50 to tilt the bell crank 75 in a counter-clockwise sense, and consequently the slidable tucker member 42 begins to travel upwards, quicker than the plunger itself does, until it touches the 55 underside of the cigar. Thereupon it moves in unison with the elevating plunger 3, but before the latter has quite reached its highest position, the lug 86 of the bell crank comes into contact with the downwardly extending stop 87, fixedly 60 attached to the feed table F, rocking the bell crank 75 in a clockwise direction during the remaining upward movement of plunger 3. The tucker finger 42, thus drawn away from the cigar, permits the member 41 to swing the ungummed band end over the tip of the tucker finger. As soon as however the plunger begins 65 its downward course, while the cigar is held suspended by the wrapping jaws 36-37, as explained, the tucker finger 42 upon release of the stop 87, moves quickly upward under tension of the spring 84 and presses the ungummed end of the band fully against the underside of the cigar, as can be seen in Fig. 5. As the plunger continues its descent, the pulling action of spring 70 84 ceases, allowing the control arm 81 to move

down, away from screw stop 85 whereupon the tucker 42 returns to its lowered position in its relation to the plunger. The member 41 simultaneously has returned to its retracted position, and after the completion of the banding and wrapping operation the cigar which now rests upon the plate 49 and is held in place by the feeler bar 44, is removed sideways to a heat-sealing device, as mentioned before.

In accordance with the provisions of the patent 10 statutes, I have described my invention, but I desire it understood that it is not confined to the particular form shown and described, the same being merely illustrative, and that the invention can be carried out in other ways without departing from the spirit of my invention, and therefore I claim broadly the right to employ all equivalent instrumentalities coming within the scope of the appended claims, and by means of which, objects of my invention are attained and new results 20 accomplished, as it is obvious that the particular embodiments herein shown and described are only some of many that can be employed to attain these objects and accomplish these results.

Having now described my invention, what I 25 claim as new, and desire to secure by Letters Patent, is:

1. A cigar banding and wrapping machine, comprising means to convey a cigar with a loose band, provided with moistened adhesive and a 30 loose wrapper superimposed over the band into a banding and wrapping position and means to adhesively close the band next to the cigar, around the latter, and to securely close a wrapper over both, while the cigar is held stationary during 35 these operations.

2. The combination with a cigar banding and wrapping machine comprising a cigar feeding device, adapted to convey cigars, originally adjacently arrayed, in a rectilinear path and with 40 intermittent stops toward a wrapping and banding position; of a cigar spacing device, adapted to separate and evenly space said cigars from a predetermined point before they reach said position, and a single guiding rail, running alongside the 45 rectilinear path at a small angle and adapted to gradually shift the cigars endwise into a centering alignment with the predetermined wrapping and banding position.

3. In a cigar banding and wrapping machine, 50 the combination with a cigar feeding device, comprising means to deliver cigars in spaced relationship into a wrapping and banding location; of a cigar centering device adapted to adjust the position of the leading cigar when delivered into 55 said location, said device comprising a jaw, serving as a stop to limit the forward motion of said cigar and consisting of an upright one-armed lever, pivotally fastened at the lower end 60 and contacting with its free end the front side of the leading cigar, and another jaw contacting the rear side of said cigar and arranged in such a way that it does not interfere with the cigar-spacing and delivering means, said jaw consisting 65 essentially of a horizontal swing suspended over the cigar spacing and delivering device and formed at the free end in the shape of a clamping jaw, positioned opposite to the first jaw, and means to make the jaws converge yieldingly to 70 each other until they contact the cigar, irrespective of its thickness.

4. In a cigar banding and wrapping machine for applying a gummed band about a cigar and enclosing the banded cigar within a wrapper, the 75

combination with a pair of wrapping jaws adapted to fold said wrapper, with the band underneath it, around three sides of the cigar; of a spring controlled hook-shaped folding finger 5 operatively connected with one of said wrapping jaws and adapted with its hook-shaped end to automatically fold a portion of the adjacent free lateral edge of the wrapper together with the adjacent end of the band underneath the fourth 10 side of the cigar for further wrapping operations, means to reciprocate this same wrapping jaw in a vertical direction and mechanical means to control the action of the folding finger in such a way that it performs said function when the wrapping 15 jaw is lowered and contacts with the wrapper, and becomes inactive when the wrapping jaw is raised.

5. In a cigar banding and wrapping machine for applying a gummed band about a cigar and enclosing the banded cigar within a wrapper, the 20 combination with a cigar elevating plunger adapted to carry a cigar with a band and wrapper, superimposed upon each other in the order named, into a stationary banding and wrapping position, and a pair of wrapping jaws adapted to fold 25 said wrapper and band against three sides of the cigar and means to deflect one band end over the

edges of the fourth side; of a tucker device, adapted to press said deflected band end firmly against said fourth side, said device being slidably guided in a vertical slide on the cigar elevating plunger, and of means to elevate the tucker device within 5 said vertical slide independently from the upward travel of the plunger.

6. In a cigar banding and wrapping machine for applying a gummer band about a cigar and enclosing the banded cigar within a wrapper, the 10 combination with a cigar elevating plunger adapted to carry a cigar with a band and wrapper, superimposed upon each other in the order named, into a stationary banding and wrapping position, and a pair of wrapping jaws adapted to 15 fold said wrapper and band against three sides of the cigar and auxiliary means to bend one end of the cigar band toward the middle of the fourth side of the cigar; of a tucker device adapted to press said band end firmly against said side, said 20 device being slidably guided in a vertical slide on the cigar elevating plunger, and of means to elevate the tucker device within said vertical slide independently from the ratio and speed of the plunger. 25

FRANCIS X. MALOCSAY.
